(57) **CLAIM**

The ornamental design for shoulder strap for bag, as shown and described.

DESCRIPTION

1. Shoulder strap for bag

1.1 : Perspective

1.2 : Front

1.3 : Back

1.4 : Right

1.5 : Left

1.6 : Top

1.7 : Bottom

The shoulder strap forms a series of elongated and more or less elliptical elements, which on one side of the shoulder strap have an anchor chain link design; the dotted lines in the images represent seams that are not part of the design and are not claimed.
